UNITED STATES PATENT OFFICE.

CLINTON LAVERNE ADAIR, OF BENTON, PENNSYLVANIA, ASSIGNOR OF ONE-HALF TO
KARL ZARR HESS, OF BENTON, PENNSYLVANIA.

DEMOUNTABLE-RIM RETAINER.

1,208,439.

Specification of Letters Patent. Patented Dec. 12, 1916.

Application filed June 29, 1916. Serial No. 106,630.

To all whom it may concern:

Be it known that I, CLINTON LAVERNE ADAIR, a citizen of the United States, and a resident of Benton, in the county of Columbia and State of Pennsylvania, have invented a new and Improved Demountable-Rim Retainer, of which the following is a full, clear, and exact description.

This invention relates to resilient tires and 10 wheels and has particular reference to demountable rims for pneumatic or other replaceable tires.

Among the objects of the invention is to provide a quick and easy means for manipulating demountable rims or the like.

More definitely stated, one object is to provide in connection with the demountable rim, a hook-like retainer with means for quickly applying the same to position and 20 tightening for locking the rim in place.

With the foregoing and other objects in view the invention consists in the arrangement and combination of parts hereinafter described and claimed, and while the invention 25 is not restricted to the exact details of construction disclosed or claimed herein, still for the purpose of illustrating a practical embodiment thereof reference is had to the accompanying drawings, in which like 30 reference characters designate the same parts in the several views, and in which—

Figure 1 is a side elevation of a wheel showing my improvement applied thereto; Fig. 2 is an enlarged detail view of the 35 locking devices partly in section; Fig. 3 is a view of the coupled ends of the hoop partly in section, and showing the position prior to tightening; Fig. 4 is a horizontal sectional detail on the line 4—4 of Fig. 1, 40 indicating the position of the clamp when the hoop is tightened; Fig. 5 is a transverse sectional detail on the line 5—5 of Fig. 2; Fig. 6 is a transverse sectional detail on the line 6—6 of Fig. 7; Fig. 7 is a detail in 45 elevation of a modification of the invention applied to that type of rim shown in Fig. 6; and Fig. 8 is a transverse sectional detail of the felly and rim portions of a modified form of the invention.

50 Referring now more particularly to the drawings, I show in the principal figures a standard form of wheel comprising a felly 10, a stationary rim 11 and a demountable rim 12 carrying any approved form of tire 55 indicated at 13. The stationary rim 11 is

held from displacement in one direction by means of a series of lugs 14 clamped to the felly by means of transverse bolts 15. Any suitable number of these bolts 15 or their equivalent may be employed, and upon the 60 outer end of each of them, or on the side of the felly opposite the lug 14 is secured a special form of lug 16 having its outer end beveled as indicated at 17. The beveling or 65 flare of the outer ends of these lugs is outward and the point of each lug projects radially far enough beyond the outer surface of the felly to form a seat for my special binding hoop 18, which bears at its one side against the bevels 17 of the several lugs 16, and at its other side against the demountable rim 12.

As shown in the detail views, one end of the hoop is provided with a closed ring or eye 19 of circular form and the other end 75 of the hoop is threaded, as indicated at 20.

At 21, I show a socket member having an internally threaded thimble 22 at one end 80 adjustably connected to the threaded end 20 of the hoop. At its other end, the socket member is bifurcated having two parallel wings 23 and 24 having coaxially arranged holes 23' and 24' respectively. These holes are both circular, but the former is larger 85 than the latter.

At 25, is shown a short shaft having at one end a head 26, adjacent which is a large circular bearing portion 27 fitted for rotation in the hole 23'. Near the other end the shaft is provided with a second smooth bearing portion 28 rotatably fitted 90 in the hole 24'. Between the bearing portions 27 and 28 is a polygonal portion 29 formed as reduced from the bearing portion 27, whereby this portion of the shaft is projectable through the bearing hole 23'. The length of the portion 29 is greater than the diameter of the metal of the hoop or thickness of the ring 19. At the end of the shaft 95 opposite the head 26 is formed a polygonal portion 30 reduced from the portion 28 for projection through the hole 24'. This portion 30 is adapted for the application of a wrench of any suitable construction for 100 turning the shaft.

31 indicates a cam wheel having a circular periphery and fitted rotatably within the ring 19. This wheel 31 has an eccentric opening 31' into which the polygonal portion 29 of the shaft fits. The portion 29, 110

however, of the shaft is longer than the thickness of the wheel for the accommodation of a stop lug 32 fitted rigidly upon said projecting end of the portion 29. The wheel 5 and lug 32 consequently are both rotatable with the shaft between the two plates 23 and 24 of the socket member. The length of the stop lug 32 is such that its free end is adapted to strike against the crotch portion 10 of the socket member 21.

The operation of the device thus far described is substantially as follows: With the felly equipped with the bolts 15 and lugs 16, the rim 12 is slipped into place against the 15 flange of the rim 11 over the lugs 16 and then the hoop, with the coupling thereof in the position shown in Fig. 3, will be slipped into place over the lugs 16 and against the adjacent side of the rim 12, as shown in Fig. 20 5. The length of the hoop will previously have been adjusted at the connection at 20 and 22 according to the size of the wheel. The tool (not shown) then being applied to the polygonal end 30 of the shaft 25, the 25 shaft, cam wheel, and stop lug 32 will be swung within the ring 19 until the stop lug strikes against the crotch portion of the socket piece. The longer radius of the cam wheel will by this time have passed to or 30 slightly beyond the dead center and accordingly the device will be self-locking, as shown in Figs. 1, 2, and 4. The amount of eccentricity of the cam wheel will be sufficient to firmly tighten the hoop in the position indicated, preventing displacement thereof from the wheel and the hoop will hold the other parts of the wheel in place.

In Figs. 6 and 7, I show a modified form 40 of rim structure, the same comprising a stationary rim 11' secured in any suitable manner to the felly 10. The rim 11' is provided with a side edge formed with a groove 33 over which the demountable rim is adapted to be passed so as to abut against the 45 standing flange 34 on the other side of the wheel. To adapt this form of fixed rim for the improved retainer, a portion of the projecting or grooved portion of the rim is cut away close to the edge of the felly 10 to accommodate the coupling portions of the 50 hoop. In order to support the ends of the

grooved portion of the rim thus exposed, a pair of lugs 16' are bolted to the felly by means of bolts 15. The hoop lies in the groove 33 entirely around the wheel except 55 directly between the lugs 16', and when so lying in the groove, as shown in Fig. 6, the detachable rim will be positively locked in place. The operation of this form of device is practically the same as that above described in connection with the main figures. 60

As shown in Fig. 8, the pivot bolt 25' may be journaled permanently in a sleeve 10' fitted in the felly 10 and reversed so that the end 30 to which the wrench or the tool will 65 be applied, will be on the side of the wheel next to the vehicle. By this arrangement the head 26 and adjacent parts of the device will project on the outside of the wheel to the least extent. The bolt 25' may be locked 70 in place by a washer 35 and key 36.

I claim:

1. The combination with a felly, a rim fixed thereto and a demountable rim coöperating with the fixed rim, of retaining 75 means for the demountable rim comprising a hoop having a ring at one end, a bifurcated socket piece at the other end, the ring being located in the bifurcated portion of the socket piece, a crank shaft journaled in 80 the socket piece and a cam wheel secured to the crank shaft and fitted rotatably in the ring for tightening the hoop, and means secured to the side of the felly to hold the hoop in place against the demountable rim. 85

2. The combination with a felly and a rim secured thereto, of a demountable rim retainer coöperating with said felly and rim and comprising a hoop having at one end a circular ring and at the other end a bifurcated socket piece adjustably connected thereto, said ring being fitted into the forked portion of the socket piece, a shaft journaled in the socket piece and having a polygonal portion between its ends, a cam wheel 90 secured upon the polygonal portion of the shaft and fitted for rotation within the ring aforesaid, means to rotate the shaft and cam wheel and a stop member secured to the shaft to limit its extent of rotation. 95

CLINTON LAVERNE ADAIR.
